UNITED STATES PATENT OFFICE.

ROCHFORT WYBRANTS ROBINSON, OF MARLOW, ENGLAND.

PARALLEL AND SECTIONAL RULER.

Application filed January 11, 1922. Serial No. 523,436.

To all whom it may concern:

Be it known that I, ROCHFORT WYBRANTS ROBINSON, a subject of the King of Great Britain and Ireland, and a resident of Marlow, county of Buckinghamshire, England, have invented a certain new and useful Improvement in Parallel and Sectional Rulers, of which the following is a specification.

This invention relates to an improved parallel and sectional ruler, with which parallel lines can be ruled at any required distances apart, without making separate measurements, and which can be set for any given spacing up to the limit of its capacity, and a series of lines ruled quickly with that spacing.

As a sectional ruler it can be set quickly for any spacing.

As a parallel ruler it combines several distinct features.

1. A series of parallel lines can be ruled, each line being at any desired distance from the preceding one, without making any measurements.

25 2. Any required number of parallel lines can be ruled, at equal distances apart, and in such a way that the last line shall be at any required distance from the first, thus dividing a given space into any required number 30 of equal parts.

3. The ruler can also be so set that, starting with a very close spacing, which can be as close as desired, and then increasing the spacing, between each line ruled and the preceding one, a predetermined amount each time to a certain point, and then reversing the operation, a perfectly regular shading effect, for a circular column, or shaft, can be produced, and in such a manner that the last 40 line will be at any required distance from the first, thus uniformly shading-in a column or shaft, or other circular object, of any given diameter.

Broadly, the invention consists of mounting one member of the ruler slidably within or on an inclined edge of the other, the inclined edge or co-acting edge being graduated, the operation of sliding what will be termed the inner member along said edge 50 spacing the opposite edge of the inner member a specified distance (according to the graduation slid to) from an edge of the other or outer member. The latter is then slid on the inner member which is held still 55 until the spaced edges abut, and the ruling edge of the outer member will then have

travelled the specified distance from the last position. Various other features are, or may be, used, all as will be seen from the following description and the accompanying 60 sheets of drawings, wherein:—

Figure 1 is a plan; and,

Figure 2 an inverted plan of the device; whilst,

Figure 3 represents the inner sliding 65 member.

Figure 4 shows a section of the frame through the line *k*, *k* in Figure 1; and

Figure 5 shows a section through the line *l*, *l* in Figure 1. 70

Figure 6 is a view similar to Figure 1, but showing a modified construction of ruler for use in conjunction with a straight edge.

Figure 7 is a plan view of an alternative simplified construction of ruler. 75

Figure 8 is a plan view of a detachable scale employed in the construction of ruler shown in Figure 6.

Figure 9 is an underside plan view illustrative of the construction of the slidable 80 triangle of the ruler.

Figure 10 represents a modified construction in which a lever pointer takes the place of the sliding pointer and disc shown in Figure 6. 85

Figure 11 is a view of the stop employed in such modified construction.

Like letters of reference indicate corresponding parts in the several figures.

In carrying out the invention, and referring first to Figures 1 to 5 of the accompanying drawings, the ruler consists of a frame *a*, containing an inner member *b*, constituting a sliding triangle, said frame consisting of two layers with openings through them of 90 different forms. The form of the opening in the upper layer is seen in Figure 1; the form of the opening in the lower layer is seen in Figure 2. When the two layers are superimposed they form a truncated triangular frame with recesses on both its upper and lower surfaces, as shown in the drawings. The triangle *b* slides in the triangular recess formed by the opening in the lower layer of the frame *a*, a portion of each 95 end of said triangle always being under the upper layer of said frame. A wing *b'* attached to the upper side of the triangle *b* is accommodated by the opening in the upper layer of the frame *a*, but does not come into 100 contact with the edges of the opening, as shown in Figures 1 and 5. The wing *b'* 110

projects over and rests on the lower layer of the frame, but is raised above it when the frame is on a flat surface, as shown in Figures 1 and 5. The triangle b is thinner than the lower layer of the frame, so that, on a flat surface, it moves easily under the upper layer as shown in Figure 5. A lever c is attached to the upper side of the frame by a suitable bolt d secured by a nut d' , preferably countersunk in the underside of the frame as shown in Figure 4. The nut d' is tightened sufficiently to keep the lever c from being too easily moved. On the underside of the lever c , near its upper end, is secured a round stud e , which projects through an opening f , in the form of an arc, in the frame; this stud nearly reaches the level of the under surface of the frame and regulates the amount of the movement of the triangle b in the frame, as shown in Figure 2. A graduated scale g is provided, over the opening f , in conjunction with which scale a pointer line e' on the lever c regulates the opening for which the lever is set, and there is another scale h on the frame on which the line b^2 on the triangle b also registers the spacing. These scales are shown graduated to sixty-fourths of an inch, but they can be graduated in any manner desired.

30 The flat wing b' attached to the upper side of the triangle b keeps it from falling out of the frame. The holes i , sunk in the upper side of the frame, and the similar hole j , sunk in the triangle b , are for the tips of the fingers to facilitate the sliding of the frame and triangle on the paper. The ruling edge a' of the frame, and the straight edge a^2 are preferably formed at right angles, so that the ruler can be used as an ordinary set square.

35 The method of using this improved ruler as a sectional ruler is as follows:—

To rule a series of parallel lines spaced at equal distances, the pointer line e' on the lever c , Figure 1, is moved into alignment with the graduation on the scale g , representing the distance required, and the first line having been ruled, along the ruling edge a' , the frame is held in place, whilst the triangle b is moved towards the lever c , with its lower edge in contact with the frame, till it is stopped by the stud e on the pointer c . The triangle then being held in place on the paper, the frame is moved down into contact with its upper edge, and the next line is ruled, and the same process is repeated for each line. Any number of parallel lines equally spaced can thus be ruled, and sectional shading with any desired spacing produced.

40 The method of using this ruler as a parallel ruler is as follows:—

To rule two lines at a given distance apart, the lever c is moved out of the way, towards the left hand end of the scale g , and the first line having been ruled as before, another can

then be ruled at any required distance from it, by sliding the triangle b , with its lower edge in contact with the frame, which is held in place till the fixed pointer b^2 on the triangle b registers the distance required on the scale h below it, Figure 1. The triangle then being held in place, the frame is brought down into contact with it as before and the next line ruled. Another line can then be ruled at any required distance from this last one in the same manner. Should the spacing required be greater than the compass of the scale, two or more sliding movements of triangle and frame can be made.

45 Referring now to the construction of ruler shown in Figure 6.

The lower edge a^2 of the frame a is also graduated, as shown, so that it can be used in conjunction with a straight edge, on which a starting line has been marked. This permits of spacing a line at a distance from another which would necessitate several movements of triangle and frame in the ordinary way.

50 The scale h , Figures 6 and 8, is removable from the frame a , and is graduated for 1/64th on one edge, and millimeters on its opposite edge, so that by reversing said scale, measurements can be made by the metric system. This scale may also be graduated on both edges of its reverse side, so that it may contain four separate scales. It has a slight longitudinal movement in the frame a , and is held in place by a spring h' ; it can thus be kept as accurately adjusted as may be necessary to compensate for any slight variation, caused by expansion, or shrinkage of frame or triangle. Extra scales can easily be made on a piece of card for special work or exact duplications.

55 A pointer b^3 is slidably mounted under the wing b' of the triangle b , to register with the upper graduations on the scale h , and a snail or spiral disc k is rotatably mounted on the triangle b to register with a scale k' on said triangle b , and engage, when required, with the slidable pointer b^3 .

60 The working of this form of ruler, for parallel lines and sectioning, is the same as described with reference to the previous form of ruler, but to rule a given number of parallel lines equally spaced so that the last shall be any required distance from the first, thus dividing a given space into the required number of equal parts, the sliding pointer b^3 on the triangle b is used instead of the fixed pointer b^2 . The total distance is expressed in sixty-fourths of an inch, and this number is divided by the number of spaces required, carrying out to two decimal places. The snail or spiral disc k is set to register the fraction of the result, and the sliding pointer b^3 is pushed up against the disc. The integer of the result is the num-

- ber of sixty-fourths on the scale h with which the sliding pointer b^3 must be made to register for each line. For instance:—
 To rule parallel lines which shall divide, a 5 $1\frac{1}{4}$ inch space, into eleven equal parts. $1\frac{1}{4}$ equals 80 sixty-fourths. 80 divided by 11 equals 7.27. The spiral disc k is set to register 27 on the scale k' and the sliding pointer b^3 is moved into contact with said 10 disc, and for each line the triangle b is moved as described above, till the pointer b^3 registers 7 on the scale h . If a series of lines be ruled with this setting, the twelfth will be $1\frac{1}{4}$ inch from the first, and the space will be 15 divided into eleven equal parts. In the above case, the frame a and triangle b could be held in place, at the start, with the pointer b^3 registering 7 on the scale h , and the lever c be moved up against the triangle b , and the 20 ruling could then be done as described above for sectional ruling.
- To rule parallel lines which shall produce a shading effect on a circular column, or shaft, or other cylindrical object:—
 25 The working of the arrangement by which this is accomplished is based on the fact that if a series of parallel lines be ruled, at gradually increasing distances apart, and so that, taking the distance between the first and second as the unit of measurement, the distance between the second and third be made two units, and that between the third and fourth three units, and so on to any point, and then the process be reversed, decreasing the spacing one unit at each step, till a spacing of one unit is again arrived at, only one of the largest spaces having been produced, then the distance from the first line ruled to the last, in these same units, 30 will be the square of the number of units in the largest space ruled. Therefore, if the unit used is $1/64$ th inch, to go up to $8/64$ ths and back, as above described, would produce a total width of $64/64$ or 1 inch.
 35 To go up to $9/64$ and back, would give a width of $81/64$. So that to thus shade in a column of $1\frac{3}{16}$ inch diameter, with a scale, graduated to sixty-fourths of an inch, the spacing would have to increase, for eight 40 steps, a little more than $1/64$ th inch at each step. As the difference between the square of a number, and that of the next higher number, is the sum of the two numbers, in the present case 17, and as the difference 45 between the square of 8 and 76 is 12, it follows that for $76/64$, each space will have to be $1/64$ plus $12/17$ of $1/64$, which, expressed as a two-place decimal fraction is .71. The ruling is therefore done by setting the spiral disc k to 71, sliding the pointer b^3 into contact with it, and then proceeding as before, using the pointer b^3 , and registering $1/64$ for the first step, that is, for the first line from the starting line, $2/64$ 50 for the second, and so on, up to $8/64$ and

back again. Each distance registered by the pointer b^3 is increased by the fraction of $1/64$ inch, for which the spiral disc k is set.

In practice, the calculation, for any diameter of this style of ruling, can be made very 70 easily by using the following table, which accompanies each ruler, and gives opposite each number its square and the fraction to be added for each sixty-fourth of an inch over that square, it being only necessary to 75 multiply the fraction by the number of sixty-fourths by which the desired shading exceeds the next lowest square number. For the above case, opposite 8 is found 64 and .059, which last multiplied by 12 gives .71 to 80 two places as above.

Table giving numbers, with their squares and the fraction, to be added for each sixty-fourth of an inch, that measurement desired exceeds square number.

95

Should finer shading be desired, the calculation, in units of $1/128$, can be made from the same table, by basing the calculation on double the diameter desired, expressed in sixty-fourths. To shade the above size 100 column; 76 multiplied by 2 equals 152, the highest square below which is 144, the square of 12, the difference is 2, and multiplying the fraction .04 (found in the table opposite 12) by 8 gives .32, the spiral disc k is therefore 105 set to half of this, or 16, and the shading started on $1/128$ graduation, and increased one of these, each time, to 12 and back. Still finer shading can be produced with unit of 110 $1/256$, and by using differently graduated scales, with units of $1/96$ and $1/192$.

In practice, it is found that as the width of the first space, in this style of shading, varies nearly 100 per cent, according to the setting of the disc k , the appearance of the 115 shading is somewhat spoiled, and for this reason, the actual rule for setting the disc k and ruling the lines at the start and finish, is a modification of the above, as follows:—
 2 is subtracted from the number of sixty-fourths representing the desired width of the shading, and the first and last lines are ruled at $1/64$ or $1/128$, etc., as the case may be, as set by the fixed pointer b^2 on the triangle b and the rest by the sliding pointer b^3 as before.

It is obvious that many mechanical equivalents could be substituted for the disc k to obtain similar results. For instance, a bell-cranked indicator pivoted at its angle to the 120 125 130

triangle b could be employed, having one short arm for the pointer on to the scale h and the other arm, a long arm, pointing on to an arcuate scale graduated as h' .

5 In an alternative and simplified construction of ruler above described, and shown in Figure 6, the snail or spiral disc k , the slideable pointer b^2 , the detachable scale h , and its holding down spring h' , are dispensed with, and, as shown in Figure 7, a slideable pointer or bar c' with pointer line c^2 thereon to register with the scale g , which scale g is now located on the triangle b , now takes the place of the pointer c , and by abutting 10 against the cross member m of the frame a controls the length of the movement of the triangle b . In this construction of ruler, the pointer is now made movable and adjustable to register with a fixed scale h on 15 the frame a .

Figure 9 shows the underside of the triangle b employed in the various forms of ruler. When constructed of wood, the cross pieces b^4 are set into the ends, the grain 25 running across the triangle, and they may project slightly beyond its top and bottom edges, so that any shrinkage in the material of which the triangle is constructed will not affect its accuracy. These pieces may also 30 project slightly below the lower surface of the triangle, thus being the only part in contact with the paper, thereby giving the triangle a better hold on the paper, tending to avoid slipping.

35 In the construction shown in Figures 10 and 11, the long arm k^2 of the pointer is moved to register the fraction required on the scale h' , in the same manner as it is registered by the spiral disc in Figure 6, 40 thereby setting the short arm k^3 of the pointer in the correct position for that fraction.

The long arm k^2 of the pointer is bent down at k^4 into the recess k^5 in the upper side of 45 the triangle b so that it passes freely under the cross piece a^4 .

The plate k^6 on which the lever pointer is pivoted can be adjusted by loosening the screw k^7 , so that the short arm k^3 may 50 be made to register zero on the scale when the long arm registers zero on the scale h and triangle is at the end of its motion.

A screw stop m on the cross piece a^5 is so 55 adjusted that it just keeps the triangle from jamming in the frame.

For sectional ruling, the triangle b is slid in the usual manner till the pointer registers the spacing desired on the scale, and then the stop n is slid into contact with the cross piece a^4 , when the ruler is set for that spacing.

The stop n is shown in elevation in Figure 11, to a larger scale, and is moved by simply pressing down its upper plate n' , when it can be slid to the desired position, and when released it is locked in position by the bevelled stud n^2 engaging with the bevelled under edges of the slot n^3 . The pin n^4 slides freely in the slot.

I claim:—

1. A ruler including a frame provided with a ruling edge and having an opening one side of which provides a gauge edge disposed at an angle with reference to the ruling edge, a scale on the said gauge edge, a shiftable gauge member carrying a marker adapted to be read in conjunction with said scale and said gauge member adapted to be shifted along the gauge edge to thereby be moved to a new position where it may be held while the frame is being adjusted to the new set position of the gauge member.

2. A ruler including a frame provided with a ruling edge and a gauge edge disposed obliquely to said ruling edge, a scale carried by the gauge edge, a shiftable gauge member adapted to be shifted along said gauge edge, and an adjustable pointer carried by said gauge member and adapted to cooperate with said scale.

3. A ruler including a frame provided with a ruling edge and a gauge edge disposed obliquely to said ruling edge, a scale carried by the gauge edge, a shiftable gauge member adapted to be shifted along said gauge edge, a second scale on said gauge member representing fractions of the divisions of the scale on the said gauge edge and an adjustable pointer also carried by said gauge member and adapted to cooperate with said scale, said adjustable pointer comprising a right angular lever pivoted at its angle and one arm thereof constituting the pointer for cooperating with the gauge edge of the frame and the other arm cooperating with said fractional scale.

In testimony whereof I have affixed my signature hereto this 30th day of December 1921.

ROCHFORT WYBRANTS ROBINSON.
